UNITED STATES PATENT OFFICE.

SOLOMON A. GOODMAN, OF CHICAGO, ILLINOIS, ASSIGNOR OF ONE-HALF TO GEORGE BRUCATO, OF CHICAGO, ILLINOIS.

TROUSERS.

1,130,506.

Specification of Letters Patent. Patented Mar. 2, 1915.

Application filed July 23, 1913. Serial No. 780,644.

To all whom it may concern:

Be it known that I, SOLOMON A. GOODMAN, a citizen of the United States, and a resident of the city of Chicago, county of Cook, and 5 State of Illinois, have invented certain new, and useful Improvements in Trousers, of which the following is a specification.

My invention relates to improvements in trousers and has for its object the production of a pair of trousers which shall be 10 neat in appearance, comfortable when worn and of economical construction. Other objects will appear hereinafter.

With these objects in view, my invention 15 consists in the combinations and arrangements of parts hereinafter described and claimed.

The invention will be best understood by reference to the accompanying drawing 20 forming a part of this specification, and in which,

Figure 1 is a front view of the upper portion of a pair of trousers embodying the preferred form of my invention, Fig. 2 is a 25 side view thereof, and Fig. 3 is a top plan view thereof.

The preferred form of construction as 30 illustrated in the accompanying drawing comprises a pair of trousers each leg of which is constructed of front and rear pieces 1 and 2 respectively, which pieces are connected at their adjoining edges in the conventional manner to form the inner and outer seams of the trousers legs.

35 The rearward portion of the trousers at the waist line is provided at its inner side with a lining 3 the upper edge of which is secured to the trousers pieces 2 by stitching 4. Provided at the front of the trousers at 40 the waist line are sections 5 of elastic material, the upper portions of the trousers pieces 1 being cut away in order to accommodate said sections. Said sections are secured at their rearward ends to the forward 45 ends of the lining 3, the lower edges of said sections being secured as by stitching to the upper edges of the pieces 1. The upper edge portions of the latter, that is the portions adjacent the elastic sections 5 are made full, 50 as clearly shown in Fig. 1 so as to permit of expansion in order to correspond with expansion of sections 5.

Formed integral with and forwardly projecting from the upper ends of the trousers pieces 2 are straps 6 adapted when in op-

erative positions to entirely cover the elastic sections 5 so that the latter will be unnoticeable. The straps 6 serve as will be seen in the capacity of a belt, the forward end of one of said straps being provided with a 60 buckle 7 and the corresponding end of the other of said straps being provided with spaced holes 8 whereby the strap ends may be adjustably secured together. A loop 9 is provided for coöperation with said straps 65 for retaining the same in operative positions, that is in a position in which the same will register with and completely cover the elastic sections 5.

A pair of trousers constructed as set forth 70 will present a neat and tidy appearance at the waist line, since by reason of the elastic sections 5 which lend expansibility to the trousers at the waist line, the latter will always fit snugly about the waist of the wearer. 75 Through the provision of the straps 6, the elastic sections will always be completely covered thus conduced to a neat and finished appearance, and by forming the rearward ends of said straps integral with the 80 rear pieces 2 of the trousers, an economical and durable construction is provided and one which results in a snug and perfect fit of the trousers at the hips.

While I have illustrated and described the 85 preferred form of construction for carrying my invention into effect, this is capable of variation and modification without departing from the spirit of the invention. I, therefore, do not wish to be limited to the 90 precise details of construction set forth, but desire to avail myself of such variations and modifications as come within the scope of the appended claims.

Having described my invention what I 95 claim as new and desire to secure by Letters Patent is:

1. A pair of trousers comprising front and rear portions, the rear portions extending above said front portions; elastic waist band sections stitched to the top edges of said front portions, the latter being gathered to said sections; and belt sections carried by said rear portions and extending over said elastic sections covering the latter, substantially as described. 100

2. A pair of trousers comprising front and rear portions, the rear portions extending above said front portions; elastic waist band sections stitched to the top edges of 110

said front portions, the latter being gathered to said sections; belt sections formed on said rear portions and extending over said elastic sections and covering the latter; and 5 a lining in said trousers, the rear ends of said elastic waist band sections being stitched to said lining, substantially as described.

In testimony whereof I have signed my name to this specification in the presence of 10 two subscribing witnesses.

SOLOMON A. GOODMAN.
